UNITED STATES PATENT OFFICE.

JOHN ANDERSON, OF BROOKLYN, NEW YORK.

DESIGN FOR HORSE SUN-BONNET.

Specification forming part of Design No. 5,210, dated August 22, 1871.

To all whom it may concern:

Be it known that I, JOHN ANDERSON, of Brooklyn, in the county of Kings and State of New York, have invented a new and original Design for a Horse's Sun-Bonnet, of which the following is a description, with reference to the accompanying drawing, in which—

Figure 1 is a perspective view of the bonnet, and Fig. 2 is a profile or central section of the same.

The horizontal profile of the sun-bonnet is nearly elliptical, with a hollow or indentation, *a*, in each side, somewhat nearer the rear end than the forward. The vertical profile is inclined up-

wardly from each end toward a laterally-central opening, *b*, between the hollows or indentations *a a*. Attached to the bonnet, and arranged over and some distance above this opening *b*, is a conical cap or top, *c*.

What I claim as my invention, and desire to secure by Letters Patent, is—

The design for a horse's sun-bonnet, as shown and described.

JOHN ANDERSON.
